Albert D. Judd's
3992

Design for Brackets.

PATENTED APR 26 1870

Fig. 2.

Witness,

H. L. Judd

Chas. L. Jones

United States Patent Office.

ALBERT D. JUDD, OF NEW HAVEN, CONNECTICUT.

Design No. 3,992, dated April 26, 1870.

DESIGN FOR BRACKETS.

The Schedule referred to in these Letters Patent and making part of the same.

To all whom it may concern:

Be it known that I, ALBERT D. JUDD, of New Haven, in the State of Connecticut, have invented or produced a Design for Brackets; and the following is declared to be a correct description thereof.

This design is adapted to be used in a single bracket for a shelf, in a corner bracket the design being duplicated, and the brackets set at an angle to each other, or the same design duplicated or quadruplicated may be used as a back plate for a bracket.

In the drawing—

Figure 1 a side view of the design in a single bracket, and

Figure 2 shows the same design quadruplicated to form the back plate.

The design of the shape and configuration is that of a convoluted vine-stem, branching off upwardly and downwardly, as represented at *a*, and having leaflets *b* that form both ornaments and connections between the stem-portions, and the vertical and horizontal bars *c* and *d* of the bracket, as represented.

I claim as my invention—

The design of the shape and configuration of the ornamental bracket set forth.

Signed by me this 1st day of April, A. D. 1870.

ALBERT D. JUDD.

Witnesses:

E. A. DURAND,
CHARLES IVES.
